UNITED STATES PATENT OFFICE.

FREDERICK J. OSIUS, OF RACINE, WISCONSIN.

ELECTRIC MOTOR.

1,240,802.

Specification of Letters Patent. Patented Sept. 18, 1917.

Application filed March 26, 1915. Serial No. 17,095.

To all whom it may concern:

Be it known that I, FREDERICK J. OSIUS, a citizen of the United States, and resident of Racine, in the county of Racine and

5 State of Wisconsin, have invented new and useful Improvements in Electric Motors, of which the following is a description, reference being had to the accompanying drawings, which are a part of this specification.

10 This invention relates to improvements in electric motors more particularly, although not solely, adapted for driving sewing machines and other light mechanism.

It is one of the objects of the present invention to provide an electric motor of the universal type which is adapted to automatically fit and actuate the various makes of sewing machines now on the market without the use of attachments of any kind.

20 A further object of the invention is to provide an electric motor which may be placed upon the stand of a sewing machine with its driving pulley in frictional contact with the hand wheel of the sewing machine

25 to actuate the said machine without requiring the use of means for attaching the motor to the stand or other parts of the machine.

A further object of the invention is to provide an electric motor of the portable type which is so constructed as to automatically adapt itself to fit the various types of machines now on the market and which motor will automatically clamp or exert a pressure upon the support to maintain the motor in a predetermined working position with relation to the wheel of the machine to be driven.

30 A further object of the invention is to provide an electric motor with a supporting frame or base of stepped formation shaped and constructed to fit all of the various styles of sewing machine stands now on the market.

35 A further object of the invention is to provide an electric motor which is pivotally, yieldingly mounted upon its support and is provided with a drive adapted to frictionally engage the driving wheel of the mechanism to be actuated.

40 A further object of the invention is to provide an electric motor which is of simple construction is strong and durable and is well adapted for the purpose described.

45 With the above and other objects in view, the invention consists of the improved electric motor and its parts and combinations

as set forth in the claims and all equivalents thereof.

In the accompanying drawing in which the same reference characters indicate the 60 same parts in all of the views:

Figure 1 is a side view of the improved motor shown mounted upon a sewing machine stand, the sewing machine and stand being indicated by dotted lines and a portion of the motor being shown in section;

Fig. 2 is a vertical sectional view of the electric motor taken on line 2-2 of Fig. 1;

Fig. 3 is a transverse sectional view taken on line 3-3 of Fig. 1; 70

Fig. 4 is an enlarged vertical sectional view of the motor taken on line 4-4 of Fig. 1;

Fig. 5 is a diagrammatic view of the electric connections of the motor; 75

Fig. 6 is a side view of a modified form of motor shown in connection with a sewing machine, the sewing machine being indicated in dotted lines;

Fig. 7 is a vertical sectional view thereof taken on line 6-6 of Fig. 5;

Fig. 8 is a detail view of a modified form of motor support;

Fig. 9 is a side view of a modified form of electric motor. 85

Referring to the drawing the numeral 10 indicates a sewing machine stand, 11 the arm or a portion of the frame, 12 the hand or driving wheel of the sewing machine and 13 the improved electric motor. The improved electric motor comprises in part the stepped curved base or supporting member 14, the motor casing 15 and the armature shaft 16 journaled in said casing and extending therethrough at one end. The motor casing in the preferred form is pivotally connected to the supporting member by means of a pivot bolt 17 which is secured at one end to a projection 18 of the motor casing and extends transversely and beneath said 100 casing and through eyed ears 19 of said supporting member. A screw 20 passing through the bolt and entering the projection firmly secures the pivot bolt 17 to said projection 18. A coiled spring 21 surrounding the bolt and interposed between the ears and having one end engaging the bolt and the other end bearing against the support serves to yieldingly hold the forward end portion 22 of the motor casing tilted upwardly and the forward portion of the base 105 clampingly pressing downwardly. The pro-

110

jecting end portion of the shaft 16 is provided with a slightly grooved pulley 23 preferably formed of cork or other yielding material.

5 The motor is placed upon the sewing machine stand with the pulley frictionally engaging the lower peripheral edge of the sewing machine hand wheel while under tension of the tilting spring so that when current is switched to the motor the sewing machine will be actuated. By means of the yielding tilting motor construction the pulley automatically adjusts itself to hand wheels at varying heights from the stand 10 and thus the motor is adapted to fit all makes of sewing machines now in use, and the yielding construction also provides for the base clampingly engaging the support.

In order to prevent the vibration of the 20 sewing machine from causing the motor to slide out of position on the stand the legs 24 of the base or support are provided with projecting rubber knobs 25 which bear upon the stand. The base at a medial and higher 25 plane or step is also provided with similar knobs 25' which are adapted to rest upon and engage a stand of less length than the one shown. When thus used the outer legs will hang over the edge of the stand and 30 the rear portion of the base will be supported upon the said knobs 25'.

In order to adapt the motor to machines running in either direction the commutator brushes 26 are of the radial type and are 35 mounted on a ring 27 which may be revolved a sufficient distance with relation to the pole pieces 28' of the field magnets 28 to change the polarity of said magnets and thus reverse the direction of rotation of the armature 29.

In partially revolving the brush ring 27 the respective brushes are moved into electrical contact with either the upper or lower contact plates 30 and 30' which are 45 connected to the field windings 31 and 31' of the motor. For convenience in changing the direction of rotation of the motor the brush holders 32 project through elongated openings 33 provided in the casing, and may 50 be easily moved by the user.

The brush ring and brushes are held in adjusted positions by means of a set screw 34 which is threaded through the end of the casing and impinges against the brush ring 27.

Electric current is supplied to the motor by wires 34' leading to a source of electrical supply (not shown) and the speed of rotation of the motor is adapted to be controlled 60 in any manner desired.

In the modified form shown in Figs. 6 and 7 the motor casing 15 is rigidly connected to the support and the forward legs of the support are provided with yielding 65 bolts 35 (only one being shown) which

serve to yieldingly hold the driving pulley 23 in frictional contact with the sewing machine hand wheel 12 and drive the same, and the forward legs clampingly in engagement with the support of the machine. The 70 yielding feature of the bolts with relation to the support also serves to accommodate the motor to machines having hand wheels which vary in height from the stand.

The bolts 35 extend loosely through the 75 legs of the support and are surrounded with coiled springs 36 which are interposed between the heads of the bolts and the support.

The modification illustrated in Fig. 8 is similar to the form just described with the exception that the bolts 37 (only one being shown) are threaded through the support and are turned to tilt the motor upwardly and the motor pulley 23 yieldingly into engagement with the hand wheel of the sewing 85 machine.

In this construction the cork or other material of the pulley provides the yielding engagement between the wheels, and the screws the clamping engagement between the 90 motor and the support of the machine.

Another modification is shown in Fig. 9 in which the motor is mounted in vertical position and the driving pulley 38 is yieldingly splined on the motor shaft 16' and is adapted to be positioned below the hand wheel of the machine in the manner shown in Fig. 9. A coiled spring 39 surrounding the motor shaft and interposed between the pulley 38 and the motor casing 13 serves to 100 yieldingly hold the said pulley in its uppermost position and the base clampingly in engagement with the support.

In this last mentioned form of motor the speed of rotation of the sewing machine may 105 be controlled by moving the motor toward or away from the hand wheel 12 thus locating the driving contact closer to or farther from the center of the motor pulley.

While the electric motor has been described as particularly adapted for use in driving sewing machines it is to be understood that it may also be used in driving other kinds of machines without departing from the spirit and scope of the invention. 110

In operation it is only necessary to position the improved motor upon the table or support of the mechanism to be driven with the motor driving pulley engaging the lower peripheral portion of the wheel of the mechanism to be driven. In this position the driving pulley will be yieldingly held upwardly in engagement with the wheel and oppositely the force holding the pulley upwardly will impart a tendency to the base or support of the motor to clampingly engage the support of the mechanism being driven, thus maintaining the motor in a working position without the necessity of using fastening means or marring the driven 120 125 130

machine in any manner. As the pulley of the motor has comparatively a considerable range of movement upwardly with relation to its base the motor automatically adjusts 5 itself to suit varying distances between frame and wheel in various machines. The stepped formation of the base member provides for resting the motor upon machine tables or frames having offset portions or 10 planes or upon tables which vary in length from the machine arm to the adjacent outer end of the table thus forming in substance a portable, universal motor for operating various types and kinds of machines.

15 From the foregoing description it will be seen that the invention is of simple construction and is well adapted for the purpose described.

What I claim as my invention is:

20 1. An electric motor, comprising a support having a plurality of projecting knobs extending in different planes, a motor member pivotally mounted thereon and provided with a yielding friction driving pulley, and 25 means for yieldingly tilting the pulley portion of the motor member in a direction toward the wheel to be driven thereby.

2. An electric motor, comprising a support having a plurality of downwardly projecting knobs, some of said knobs being positioned on a higher plane than other of said knobs, a motor member pivotally mounted on the support and provided with a yielding friction driving pulley, and a coiled spring 35 engaging the support and the motor member for yieldingly tilting the pulley portion of the motor member in a direction toward the wheel to be driven thereby.

3. An electric motor, comprising a support having a plurality of downwardly projecting yielding knobs, some of said knobs being positioned on a higher plane than other of said knobs, said support also provided with eyed ears, a motor member having a transversely extending pivot bolt 45 which extends through the eyed ears and pivotally connects the motor member to the support, said motor member also having a yielding friction driving pulley, and a coiled spring surrounding the pivot bolt and 50 having one of its ends engaging the support and the other end engaging the motor member for yieldingly tilting the pulley portion of the motor member in a direction toward the wheel to be driven thereby.

4. An electric motor, comprising a base member having a plurality of support engaging portions extending in different horizontal planes, a motor member mounted 60 upon the base member and provided with a driving pulley, and means for automatically moving the pulley portion of the motor member toward and into driving engagement with the wheel to be driven thereby.

5. An electric motor, comprising a base 65 member having a plurality of support engaging portions extending in different horizontal planes, and a motor member pivotally mounted upon the base member and provided with a shaft and friction driving pulley thereon which is automatically tilttable toward and into direct frictional driving engagement with the wheel to be driven thereby.

6. An electric motor, comprising a base 75 member having a plurality of support engaging portions, some of said portions extending in the same horizontal plane and other of said portions extending in a different horizontal plane, and a motor 80 member pivotally mounted upon the base member and provided with a shaft and a friction driving pulley mounted thereon which is automatically tilttable toward and into direct frictional driving engagement 85 with the wheel to be driven thereby.

7. An electric motor, comprising a base member having a plurality of support engaging portions extending in different horizontal planes, a motor member positioned 90 above the base member and provided with a shaft and a driving pulley mounted thereon, a pivot pin pivotally connecting the motor member to the base member, and means for automatically tilting the driving pulley 95 toward and into direct frictional driving engagement with the wheel to be driven thereby and for imparting a tendency to the base member to clampingly engage the support 100 upon which the motor rests.

8. An electric motor, comprising a base member having a plurality of support engaging portions extending in different horizontal planes, a motor member positioned 105 above the base member and provided with a shaft and a driving pulley mounted thereon, a pivot pin pivotally connecting the motor member to the base member, and a coiled spring surrounding the pivot member 110 for automatically tilting the driving pulley toward and into driving engagement with the wheel to be driven thereby and for imparting a tendency to the base member to clampingly engage the support upon which 115 the motor rests.

9. The combination with the frame and the wheel of a machine to be driven, of a motor member and its shaft and a driving wheel thereon, and a base member on which the motor member is mounted, said base member and driving wheel oppositely engaging the machine frame and machine wheel to clampingly maintain the driving wheel in engagement with the machine wheel and the base member in engagement 120 with the frame.

10. The combination with the frame and the wheel of a machine to be driven, of a

- motor member and its shaft and a driving wheel thereon, a base member on which the motor member is mounted, and means for causing the base member and the driving wheel to oppositely engage the machine frame and the machine wheel to clampingly maintain the driving wheel in engagement with the machine wheel and the base member in engagement with the frame.
- 10 11. The combination with the frame and the wheel of a machine to be driven, of a motor member and its shaft and a driving wheel thereon, and a base member on which the motor is yieldingly mounted, said motor member and base member coacting to cause the motor wheel to yieldingly and drivingly engage the machine wheel and the motor base to clampingly engage the frame of the machine.
- 15 12. The combination with the frame and the wheel of a machine to be driven, of a motor member and its shaft and a driving wheel secured to and turning with the shaft thereof, and a base member on which the motor member is pivotally mounted, said motor member and base member coacting to cause the motor wheel to yieldingly and drivingly engage the machine wheel and the base member to clampingly engage the frame of the machine.
- 20 13. The combination with the frame and the wheel of a machine to be driven, of a motor member and its shaft and a driving wheel secured to and turning with the shaft thereof, a base member positioned below the motor member, a pivot pin pivotally connecting the motor member to the base member, and a coiled spring surrounding the pivot pin and coacting with both members to cause the motor wheel to yieldingly and drivingly engage the machine wheel and
- 25 the base member to clampingly engage the frame of the machine.
14. The combination with the frame and the wheel of a machine to be driven, of a motor member and its shaft and a driving wheel secured to and turning with the shaft, a base member having a plurality of support engaging portions extending in different horizontal planes, said base member also provided with eyed ears, a motor member having a transversely extending pivot pin which extends through the eyed ears and pivotally connects the motor member to the base member, said motor member also having a yielding friction driving wheel, and a coiled spring surrounding the pivot pin and having one of its ends engaging the base member and the other end engaging the motor member for yieldingly tilting the motor wheel into engagement with the machine wheel and the base member clampingly into engagement with the machine frame.
- 30 15. The combination with the frame and the wheel of a machine to be driven, the lower portion of said wheel being positioned above a portion of the frame, of a motor member and its shaft and a driving wheel secured to and turning with the shaft thereof, and a base member on which the motor member is mounted, the motor wheel and a portion of the base member being interposed between the machine frame and the lower peripheral portion of the machine wheel, said motor wheel frictionally engaging said lower peripheral portion of said wheel and the base portion clampingly engaging said frame portion.
- 35 In testimony whereof, I affix my signature. 80
